UNITED STATES PATENT OFFICE.

CLIFFORD E. ALLISON, OF PORTLAND, OREGON.

HOISTING DEVICE.

1,413,884.

Specification of Letters Patent. Patented Apr. 25, 1922.

Application filed November 18, 1920. Serial No. 424,982.

To all whom it may concern:

Be it known that I, CLIFFORD E. ALLISON, a citizen of the United States, residing at Portland, in the county of Multnomah, and 5 State of Oregon, have invented new and useful Improvements in Hoisting Devices, of which the following is a specification.

My present invention pertains to hoisting devices, and it contemplates the provision of 10 a hoist that is more particularly for use in conjunction with tractors, such for instance as the well known "Fordson" tractor now in the market.

The invention further contemplates the 15 provision and construction of a hoisting device that because of its peculiar construction is adapted for ready use for towing or other pulling purposes.

The invention in all of its details will be 20 fully understood from the following description and claims, when the same are read in connection with the drawings, accompanying, in which:

Figure 1 is a side elevation illustrating 25 my novel invention as secured on a tractor.

Figure 2 is a front elevation of the clutch drum, and gears and the frame on which the same are secured at the front of a tractor.

Figure 3 is a side elevation of a portion 30 of the frame and illustrating the manner in which the crane or lifting arm and gears are secured thereto.

Figure 4 is a top plan view of the frame per se.

Figure 5 is a top plan view of the crane arm and the frame, and showing the manner in which the frame extends forwardly from the radiator of the tractor.

Similar numerals of reference designate 40 corresponding parts in all of the views of the drawings:

My novel device comprises a frame having side portions 1 and the upper and lower portions 4. The said side portions 1 are provided at their lower ends with forwardly reaching arms or portions 2 and extending from the extreme outer end of the portions 2 are brace portions 3 that are also secured at one end to the upper portion 4 of the device. It will be apparent that the members 1, 2 and 3 are of angle form construction and are securely retained to each other by the bolts or other fastening means.

Secured to and extending rearwardly from 55 the portions 4 as clearly shown in Figure

1, are brace rods 5. These rods are secured to the rear axle (not shown) of the tractor and the said rods are provided with turn buckles 6 as illustrated.

Mounted on the members 3 is a driving 60 shaft 7 having pulley 8 arranged on one of its ends. Surrounding this pulley 8 is a drive belt 9 that derives motion from the drive pulley (not shown) of the tractor. The shaft 7 is provided on its end opposite the pulley 8 with a reduction gear 10, and said gear meshes with the gear 11 of the shaft 12. This shaft 12 is also provided with a gear 13, that in turn meshes with the large gear 14 of the friction clutch drum 16. This 70 drum 16 rotates on a shaft 15, through the medium of which the drum is secured on the members 3. Manifestly all of the shafts 15, 12 and 7 are arranged on the members 3.

Extending upwardly in the center of the 75 device and from one to the other of the members 4 is a shaft 17 that is secured to the lower member 4 by the fastening member 18 and to the member 4 at the upper end of the frame by the fastening member 19, and arranged on the upper end of the shaft 17 is my novel forwardly reaching crane arm 20, 80 having a pulley 22 at its extreme outer end.

Secured to a forwardly reaching portion 85 of the member 19 is a pulley 21, and at this point I would distinctly have it understood that these pulleys 21 and 22 are open at one side for an important purpose hereinafter set forth.

Adapted to pass around the pulleys 21 and 90 22 and having a hook or other securing member on one end, is a cable 23, and this cable is fixedly secured to the drum 16 and is adapted to be wound thereon.

In the practical use of the device, the 95 frame is secured on the front of the radiator of a tractor or other vehicle, and when it is desired to elevate material, the hook of the cable is secured to said material, and when power is applied to the driving pulley of 100 the tractor, motion will be transmitted through the pulley 8 to the shaft 7. The meshing of the gears will in turn transmit motion to the drum 16. This will tend to wind the cable on said drum and naturally 105 elevated the material may be and will be readily elevated.

However, when it is desired to employ the device for towing purposes, the cable is removed from the pulleys 21 and 22, by lift- 110

ing the same over the free side of said pulleys, and the cable may then be extended forwardly from the drum to another vehicle or object. In all other respects the movement of the cable for towing purposes is similar to its movement for elevation purposes.

It will be manifest that the device when not in use is not in the way, that when occasion demands, the ready access to the motor of the vehicle may be had, and moreover the construction of the frame and its appurtenances is such that they will not get out of order after a slight period of use.

15 The braces 5 and the manner in which they are retained and secured to the frame and rear axle of the vehicle assure the rigid connection of the gears and frame to the vehicle.

20 Having described my invention, what I claim and desire to secure by Letters-Patent is:—

1. In means for the purpose set forth, the combination of a tractor, a frame secured 25 to the forward portion of the tractor, a crane-arm secured on the frame, a driven-shaft mounted on the frame, a reduction gear arranged on one end of the shaft and

a pulley arranged on the opposite end of the shaft, a shaft arranged on the frame 30 beneath the first shaft, a gear that meshes with the reduction gear of the first shaft, a reduction gear formed on the second shaft and a clutch drum having a gear that meshes with the reduction gear of the second 35 shaft.

2. In a tractor the combination of a driving pulley, a driven pulley that derives motion from the first-named pulley, a frame secured to the tractor, brace rods secured 40 to the frame and to the rear axle of the tractor, a shaft on which the driven pulley is mounted secured on the frame, a drum that derives motion through a series of gears from the driven shaft, a crane-arm secured 45 on the frame, pulleys having one-free side arranged on the crane-arm and a cable secured to the drum and adapted to pass over the pulleys of the crane-arm.

In testimony whereof I have hereunto set 50 my hand in presence of two subscribing witnesses.

CLIFFORD E. ALLISON.
